[57] CLAIM

The ornamental design for an animal waterer, substantially as shown and described.

DESCRIPTION

FIG. 1 is a perspective view of an animal waterer showing our new design;

FIG. 2 is an elevational view taken from one side thereof, the opposite side being a mirror image of the side shown;

FIG. 3 is a top plan view thereof;

FIG. 4 is a rear elevational view thereof;

FIG. 5 is a front elevational view thereof; and

FIG. 6 is a perspective view of a modified form of the animal waterer shown in FIG. 1.
